M. O. Bell At

UNITED STATES PATENT OFFICE.

LOUIS T. VANCE, OF RACINE, WISCONSIN, ASSIGNOR TO RACINE RUBBER COMPANY,
OF RACINE, WISCONSIN, A CORPORATION OF WISCONSIN.

DESIGN FOR A TIRE TREAD.

Application filed September 5, 1924. Serial No. 10,684. Term of patent 14 years.

To all whom it may concern:

Be it known that I, LOUIS T. VANCE, a citizen of the United States, residing at Racine, in the county of Racine and State of Wisconsin, have invented a new, original, and ornamental Design for Tire Treads, of which the following is a specification, reference being had to the accompanying drawing, forming a part thereof, in which—

Fig. 1 is a plan view, and

Fig. 2 is a sectional view on the line 2—2 of Fig. 1 showing my new design.

I claim:

The ornamental design for a tire tread as shown.

LOUIS T. VANCE.
